DESIGN FOR A SERVICE STATION

Herbert O. Alden, Oakland, Calif., assignor to
Shell Oil Company, San Francisco, Calif., a
Corporation of California

Application March 25, 1933. Serial No. 47,584

Term of patent 14 years

To all whom it may concern:

Be it known that I, HERBERT O. ALDEN, a citizen of the United States, and a resident of Oakland, California, have invented a new, original, and ornamental Design for a Service Station, of which the following is a specification reference being had to the accompanying drawings forming part thereof.

Figure 1 is a front view of the service station.

Figure 2 is a top plan view of the service station.

Figure 3 is a side elevation of the service station.

Figure 4 is a side perspective view of the service station.

I claim:

The ornamental design for a service station as shown.

In testimony whereof, I have hereunto set my hand.

HERBERT O. ALDEN.
